TOY HEDGEHOG FIGURE

Charles B. Root, Morristown, N.J., assignor to Educational Design Associates

Filed Mar. 23, 1972, Ser. No. 283,071

Term of patent 14 years

Int. Cl. D21—01

U.S. Cl. D34—2 R

FIG. 1

FIG. 2

FIG. 3

FIG. 1 is a perspective view of the front, top and left side of a toy hedgehog figure showing my new design.

FIG. 2 is a rear elevational view.

FIG. 3 is a right side elevational view.

FIG. 4 is a bottom view.

I claim:

The ornamental design for a toy hedgehog figure, substantially as shown.
